INVENTOR
William E. Zahner.
BY *Arthur G. Brown.*
ATTORNEY

UNITED STATES PATENT OFFICE.

WILLIAM E. ZAHNER, OF KANSAS CITY, MISSOURI.

OIL BURNER.

Application filed April 7, 1924. Serial No. 704,651.

To all whom it may concern:

- Be it known that I, WILLIAM E. ZAHNER, a citizen of the United States, residing at Kansas City, in the county of Jackson and 5 State of Missouri, have invented certain new and useful Improvements in Oil Burners; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.
- 15 This invention relates to hydrocarbon fuel burners and the primary object thereof is to provide a safe, efficient and easily operated fuel burning mechanism. The invention contemplates a fuel burning apparatus 20 in which liquid fuel may be fed to an atomizer pipe discharging into an atomizing conduit connected to a vaporizing element connected to the burner element so that the fuel can be vaporized in a convenient manner.
- 25 Means is provided for causing a blast of air to pass through the atomizing conduit to co-mingle with the hydrocarbon fuel to supply the necessary oxygen to support combustion as well as to break up the liquid in 30 fine divisions so as to provide a desirable mixture as the air and hydrocarbon fuel pass through the vaporizing chamber.
- I have also provided a safety cut-off as 35 part of the apparatus so that in the event of an overflow of oil at the burner, the main supply line will be shut off. The safety cut-off is so constructed that it will cause the impeller for the air blast to cease operation when the liquid supply is cut off and 40 I may utilize a thermostat located distant from the burner so that upon a rise in atmospheric temperature the supply to the vaporizing tube will be cut off. There is a pilot burner adapted to burn constantly 45 to supply the necessary flame for the main burner, the pilot burner being adapted to be furnished with fuel by any suitable means for example the ordinary gas service pipe. There are certain other novel features 50 of my invention which will be apparent by reference to the following description in connection with the accompanying drawings in which:
- 55 Fig. 1 is a perspective view of a liquid fuel burning apparatus constructed in accordance with my invention, parts being

broken away to better illustrate certain other parts.

Fig. 2 is a longitudinal sectional view through the atomizer conduit, the vaporizing chamber, the main burner and the pilot burner.

Fig. 3 is a sectional view on the line 3—3 of Fig. 2.

Fig. 4 is a sectional view on the line 4—4 of Fig. 2.

Fig. 5 is a side elevational view of the switch control mechanism, and

Fig. 6 is an end view of the same.

Referring now to the drawings by numerals of reference:

1 designates a main liquid fuel supply line through which hydrocarbon fuel may be fed to discharge into an atomizing pipe 3, in turn discharging through the atomizer conduit 4 having a goose-neck extension 5 constituting a vaporizing chamber connected to the burner 6. The branch 7 of the pipe 3 which is within the vaporizing conduit 4 is curved upwardly at 8 in the form of a nozzle so that while there will be liquid in the branch 7 at all times, it cannot flow out of the nozzle 8 because the discharge end of the nozzle 8 is in a plane higher than the plane of the branch 7. The conduit 4 is supplied with air blasts through the medium of an air impeller shown as an electric fan 9, the motor for the fan receives current from the commercial line indicated as the conductor 10 which may be secured to the terminals 12 on the switch block 14 in which is a knife switch 15 which constitutes a circuit breaker for cutting out all of the current in certain conditions which will be explained hereinafter. The opposite side of 90 the switch block 14 is provided with terminals which are connected to a magnetic switch 16 through the conductor 17. The magnetic switch box 16 has the usual electrical connections with the motor of the fan and with a thermostat 19 which may throw the mechanism on the magnetic switch to cause certain automatic operations to take place which will be explained hereinafter. 100 20 is a solenoid which operates the valve 21 adapted to close the pipe 1. When the fan motor is shut off the solenoid will be operated through the switch box when the mechanism in the switch box is operated by the thermostat 19 so in case the temperature 110 in the zone in which the thermostat 19 is located rises beyond a predetermined degree

the mechanism in the magnetic switch box 14 will be operated to cut out the fan motor and also close the pipe 3. When the temperature falls the thermostat 19 will 15 cause the mechanism in switch box 14 to function so as to permit the valve 21 to open and also start up the fan motor. The specific construction of the mechanism in the magnetic switch box 14 is not illustrated in 20 this application because there are a number of magnetic switch boxes on the market having mechanism capable of controlling the fan motor and the solenoid and their construction is so well known by those skilled 25 in the art that it is unnecessary to elaborate on any particular form of magnetic switch box, but attention is directed to the fact that the thermostat will be effective in controlling the operation of the fan motor and the 30 oil supply to the pipe 3. When the fan motor is operating to cause the impeller to force a blast of air through the conduit 4 and the pipe is in open communication with the source of supply it is obvious that the 35 air passing through the conduit and into the extension 5 (which is in the form of a Venturi tube) that the injector action will take place so that the fuel mixture consisting of the liquid fuel and the air will enter 40 the vaporizing chamber 22 in the form of a spray where it will be heated by the pilot burner 23 located in the brackets 24 and 25 beneath it. The pilot burner 23 is supplied through a gas pipe 26 and the flame from 45 the jets or opening in the burner 23 will be directed against the vaporizing chamber 22 so as to heat the vaporizing chamber to cause the fuel to become vaporized in the manner well understood and from the vaporizing chamber the fuel is fed to the 50 burner 6 which may have slits or burner openings 27 to provide the necessary flame, the specific construction is immaterial however.

45 In order to provide a pilot flame for the burner I provide the baffles 28 and 29 which will direct the flame upwardly through the holes 30 so that there will be a flame adjacent to the slits 27 at all times. Therefore 50 when the fuel emerges through the slits it will be ignited. At the bottom of the member 31 is an overflow pipe 32. The bottom of the pipe 32 has a T-connection 33 so that oil flowing from pan 31 can discharge into 55 the receptacle or bucket 34. The bucket is suspended from a flexible connection or chain 35 which connects to the toe 36 of a counterbalancing lever 37. If the oil overflows from the pan 31, as soon as a sufficient 60 amount accumulates in the bucket 34 it will pull on the lever 37 allowing the connection 35 to slip off the toe 36 to move the switch

15 to open position by the chain portion 38 which opens the valve 21 through the magnetic switch 16 and solenoid 20. 39 is a constant pressure valve in the pipe 1 placed there to feed a definite flow of oil to the pipe outlet 8 or to the pipe 3 irrespective of variations of pressure either in the pipe 4 or on the inlet side of the pipe 1.

65 It will be apparent from the foregoing that the apparatus is entirely automatic, the pilot will be continuously lighted and the air impeller will be operating whenever the temperature is below a predetermined degree. The oil or fuel will be fed continuously unless cut out, either by overflowing or by the solenoid and whenever an abnormal condition arises the entire system will be rendered inactive. Therefore the device 70 is entirely automatic in its operation, simple in construction and safe because the oil supply and air supply can be rendered inactive immediately when there is a chance of 75 danger.

80 Attention is called to the fact that the end of the pipe 3 discharges into the pipe 4 before it reaches the burner so that the air and oil can mix. This construction permits the air and oil to flow together into the portion 22 above the preheater 23 so that the air can be heated to the temperature at which the oil vaporizes before the mixture is ignited. Ordinarily the oil flows from 85 the supply pipe cold or at such a low temperature that it does not vaporize while it is mixed with the air. By mixing the oil and air first and then raising the temperatures of both to the vaporizing temperature of the oil, there is a thorough co-mingling of 90 the air and oil vapor which clearly enhances the value of the burner and this I consider an important feature of my invention.

95 It is also to be observed that the top of the nozzle 8 of the pipe 3 is as high as the 100 horizontal portion of the pipe 1, the construction of the nozzle being such that danger of siphoning will be eliminated.

105 What I claim and desire to secure by Letters-Patent is:

110 An oil burner element comprising a casing, a ported member in the casing having a discharge end projecting through the top of the casing, burner elements on the top of the casing around the outlet of the ported element, aligning depending lugs on the ported element, a preheater underneath the ported element supported by the lugs and upwardly and outwardly inclined deflectors on opposite sides of the ported element for directing the flame from the preheater.

115 120 In testimony whereof I affix my signature.

WILLIAM E. ZAHNER.
